MOISTENING DEVICE

John B. Tweeten, Los Angeles, Calif., assignor of
one-half to Robert L. Parker, South Pasadena,
Calif.

Application July 6, 1942, Serial No. 449,970

4 Claims. (Cl. 91—51)

This invention relates to the type of copy making machines commercially known as duplicators and has particular reference to improvements in moistening devices for duplicators of the rotary type.

In such machines, a master copy bearing the imprinted matter to be copied is first placed on a cylindrical drum, rotation of which causes sheets of moistened copy paper to pass over the master sheet, thereby to receive imprint therefrom.

The most up to date moistening mechanism used in such duplicators is substantially a very simplified modification of the ink fount mechanism used in printing presses, and while this improved method is vastly superior to methods formerly used it has, so far as I have been able to ascertain, not been found capable of even distribution of the moistening fluid.

In view of the foregoing, it is the object of my invention to provide simple and inexpensive means for controlling the fluid distribution of such liquid fount moistening devices. To this end, the invention resides in the combinations hereinafter fully described and illustrated in the accompanying drawing, of which:

Fig. 1 is a front view of a duplicator moistening device embodying the invention;

Fig. 2 is a substantially corresponding end view thereof;

Fig. 3 is a sectional end view of the device taken substantially on line 3—3 of Fig. 1; and

Fig. 4 is a cross sectional end view of the device taken on line 4—4 of Fig. 1 in direction of the arrow.

The structure illustrated in the drawing is the part of a rotary duplicating machine in which copy sheets are moistened as they pass to the drum (not shown) on which the master is mounted. The devices of the invention are embodied in this structure, which comprises a moistening roller 1 and a squeegee roller 2, both mounted within a reservoir 3, all as usual in practice. These rollers are mounted to rotate in end frames 4, 5, which are set in the reservoir and are provided with notches in which bearing blocks 6, 7 are seated. It is noticed that the shaft of the moistening roller is journaled in the frames 4, 5 and that the squeegee roller shaft is mounted in the blocks 6, 7. In view of this, it is seen that the former is rotatably fixed, while the latter is horizontally movable relative thereto, and this movement is provided for the purpose of adjusting the pressure of the squeegee against the moistening roller.

5 A rod 10 is hung in lugs 11, 12 forming part of or attached to the ends of the reservoir parallel with the two rollers. Vertically disposed arms 13, 14 are rigidly secured to this rod, near the ends thereof, and the free ends of these arms are perforated to seat screws 15, 16 in alinement with the bearing blocks 6, 7. In the latter are sunk sockets adapted to receive headed plungers 17, 18, and springs 19, 20 are seated in these 10 sockets to bear against the heads of the plungers for the purpose of urging the latter against the ends of the screws 15, 16. An arm 21 is rigidly secured to and extends laterally from the rod 10. This arm is contacted by a vertically disposed screw 22 to turn the rod 10 clockwise and thereby to advance the plungers 17, 18 into the bearing block sockets against the tension of the 15 springs 19, 20.

Because the blocks 6, 7 are mounted for lateral movement in the frames 4, 5, it is seen that the pressure exerted by the springs 19, 20 thereagainst also urges the squeegee roller against the moistening roller and that the screw 22 controls the pressure in this manner applied. It is also seen that, because the arms 13, 14 are rigidly secured to the rod 10, the pressure exerted by the screw 22 is equally applied to the two plungers 17, 18. But, because it would be commercially impractical to make the two springs so perfect that they would function in exactly the same manner, it becomes necessary in addition to adjust the tension of each spring, and this may be readily effected by means of the screws 15, 16. After this individual adjustment has been 20 made, it is well to lock the screws against rotation in a suitable manner, as by check nuts 23.

25 The moistening roller is preferably made from hard, corrosion resisting material but, as usual, it is found advantageous to provide a soft rubber squeegee roller. The drawing is merely 30 illustrative of simple means of effecting squeegee roller pressure adjustment evenly along the entire contact surface thereof, and I reserve the right to embody modifications in the structure 35 shown within the scope of the claims hereto appended. It should, for instance, be clear to those versed in the art that it is within the skill of the ordinary mechanic to adapt the device of my invention to apply pressure as above described to the stationary squeegee used on some 40 of the commercially well known duplicators, by merely locating the rod 10 properly relative to such stationary squeegee.

I claim:

55 1. In a duplicator, in combination, a recepta-

cle for moistening fluid, a moistening roller rotatably fixed therein, bearings slidable within the receptacle, a squeegee roller in said bearings, a rod externally hung on the receptacle parallel with said rollers, arms on said rod near the ends thereof, adjustable elements at the end of each arm, resilient compressible members between said elements and the said bearings, the tension of each of which is individually regulated by manual adjustment of said elements, and adjustable means forcing the elements against the said compressible members to vary the pressure of the squeegee roller against the moistening roller.

2. In a duplicator, in combination, a receptacle for moistening fluid, a moistening roller rotatably fixed therein, bearings slidable within the receptacle, a squeegee roller in said bearings, a rod externally hung on the receptacle parallel with said rollers, arms on said rod near the ends thereof, adjustable elements at the ends of said arms, compressible members between said elements and the said bearings, an arm on the outer end of said rod, and a screw seated in threaded lugs of the receptacle for adjustably applying pressure against said last named arm to vary the pressure of the squeegee roller against the moistening roller.

3. In a duplicator, the combination with a receptacle for moistening fluid, a moistening roller, a squeegee roller, and bearing blocks for the latter slidably mounted within said receptacle;

of a rod externally hung on said reservoir parallel with said rollers, an arm at each end of said rod, resilient means operatively interconnecting said arms with the said squeegee roller bearing blocks to move said roller against the moistening roller, manually operable means on the free end of each arm bearing against said resilient means for adjusting the tension thereof, an arm on the end of said rod, and an adjustable member mounted on the receptacle and manually operable to apply pressure against the last named arm thereby to rotate said rod to vary the pressure of the squeegee roller against the moistening roller.

4. In a duplicator, the combination with a receptacle for moistening fluid, a moistening roller, a squeegee roller, and bearing blocks for the latter slidably mounted within the receptacle; of a rod externally hung on said reservoir parallel with said rollers, arms on said rod near the ends thereof, adjustable elements in the outer ends of said arms, compressible resilient members freely bearing against said bearing blocks, plungers in the outer ends of said resilient members contacted by said elements for individually adjusting the tension of said members, an arm on the end of said rod, and an adjustable member manually operable to apply pressure against said last named arm to rotate the rod thereby to vary the pressure of the squeegee roller against the moistening roller.

JOHN B. TWEETEN.
